METHOD AND APPARATUS FOR
ELECTRICAL HEATING

Ralph A. Rusca, New Orleans, La., assignor to
United States of America as represented by the
Secretary of Agriculture

Application January 5, 1945, Serial No. 571,498

1 Claim. (Cl. 219—47)

(Granted under the act of March 3, 1883, as
amended April 30, 1928; 370 O. G. 757)

1

This application is made under the act of March 3, 1883, as amended by the act of April 30, 1928, and the invention herein described and claimed, if patented, may be manufactured and used by or for the Government of the United States of America for governmental purposes without the payment to me of any royalty thereon.

This invention relates to methods of and apparatus for heating textile materials by the action of electrostatic fields created by high frequency electrical currents.

The art of using high frequency electrostatic fields for producing heat in materials is well known, but heretofore no successful application of the art has been made to heating, drying or treating of textile materials, in the form of roving, yarn, cord, rope or sheet, in a continuous process. In general, heating such materials in a continuous process is very difficult because the relative low density and thinness of the material is conducive to electrical inefficiency and electrical flashover between the applicator electrodes. This is especially true when water or other solvents are being evaporated from the material because the vapor emitted forms a low resistance electrical path between the electrodes, resulting in flashover with attendant damage or destruction of the material being heated. An excessively wide space between the electrodes may obviate this trouble to some extent, but will require higher potential on the electrodes to obtain the same rate of heating as secured with narrow electrode spacing, and this higher potential is in itself a source of inefficiency and flashover.

The general object of this invention is to provide a commercially practical and efficient apparatus for uniform heating, drying, or otherwise treating of textile materials in a continuous process.

This invention is especially applicable to the rapid drying of cotton cord used in the construction of pneumatic vehicle tires after the cord has been subjected to a treatment wherein water or other solvent has been employed. In this particular application, it is usual to wet the cord and then dry the cord while it is stretched and held under tension. Electrically or steam-heated hot plates are customarily employed for drying the cord, but with this method proper contact between the cord and the heated plate is hard to maintain, resulting in non-uniform drying, and the hot surface causes glazing of the periphery of the cord, thereby detrimentally af-

feeting the cord's properties of adhesion to rubber, which are important in the subsequent vulcanization process.

In general, this invention is based on a novel method and apparatus whereby uniform heating of the cord is obtained, and all glazing of the periphery of the cord is completely eliminated. In fact, due to certain characteristics of the method, the periphery of the cord is somewhat roughened, thereby increasing its adhesive properties.

Although this invention is hereinafter described in connection with the application thereof to the heating of cotton cord, it is not limited to this type of material and is generally applicable to all operations that involve heating, drying or treating of textiles, paper and like materials in a continuous process. This invention can also be used for the curing or polymerization of plastic or resin impregnants in such materials. Other objects, advantages, and uses of the invention will become apparent from the following description of various embodiments thereof, in conjunction with the accompanying drawing illustrating the embodiments.

In the drawing:

Figure 1 is a plan view of one form of the apparatus in accordance with this invention.

Figure 2 is a side elevational view along the line 2—2 of Figure 1.

Figure 3 is a section along the line 3—3 of Figure 1.

Figures 4, 5, and 6 are views similar to Figure 3 of three additional embodiments, respectively, of the apparatus of the invention.

Referring with more particularity to Figures 1, 2, and 3, in which like numerals refer to like parts, the embodiment illustrated comprises a suitable base 11, upon which bus bars or cables 12 and 13 are secured by means of electrical insulating cleats 14, 15, 16, and 17 that are attached to the base 11. Between the bus bars 12 and 13, there is disposed a row of metallic plates 18, each having an aperture 19 therethrough. Each plate 18 is electrically connected to and structurally supported on one of the bus bars by means of electrically conducting brackets 20. The connections of the plates to the bus bars, however, are in staggered relation so that any consecutive pair of plates is connected to opposite bus bars. The plates 18 are disposed so that the apertures thereof are in alignment to permit the continuous passage therethrough of the material to be treated, such as the cord 21 shown in the drawing. The cord may be sup-

ported at the ends of the row of plates by any suitable means, such as the rollers 22 and 23, illustrated in the drawing. By providing sufficient tension in the cord 21 between the supports 22 and 23, undue sagging may be avoided.

The bus bars 12 and 13 are connected to a source of high frequency current, such as an oscillatory generator 24 energized by a source of electrical energy controlled by a switch 25. The generator may be any suitable device, such as a vacuum tube oscillator that converts input electrical energy into output high frequency at high potential oscillations on the order of 1 million cycles per second and above. The output circuit of the generator may be resonated in any known manner and may be provided with the usual controls for adjusting the magnitude of the output energy.

In operation, the high frequency oscillations pass through the bus bars 12 and 13 and create an electrostatic field across consecutive pairs of plates 18. The cord 21, or other material to be treated, is drawn through the apertures 19 of the plates 18 by any suitable means at a predetermined rate of speed. Heat will be generated by the high frequency current within and throughout the cord. In practical use, the material will have first been treated in some manner that requires the evaporation of water, solvent or other liquid, and the heat generated will effect such evaporation. Also, if the cord has been previously exposed or treated with thermoplastic or thermosetting resins, they will become polymerized to a greater or lesser extent upon exposure to the electrostatic field, depending upon the length of time of the exposures and the power applied. In actual practice, many free ends of individual fibers on the periphery of the cord tend to erect themselves due to the influence of the field thereon. This increases the adhesive properties of the cord as compared with similar cords dried by other methods of the prior art, whereby a smooth or glazed surface is obtained. If the cord has been previously impregnated with a thermoplastic or thermosetting material in solution, the free fiber ends become encased in the polymerized material and stand out stiffly from the cord, which further increases the adhesive properties. Although in most commercial applications, the material will be treated while being drawn through the apparatus at a definite or variable speed, it is, of course, also possible to treat the material while stationary for any special purpose.

Devices for producing high frequency currents are well known in the art, and it is unnecessary to describe them fully herein. Such devices may be obtained with means for varying the output energy by means of tuning devices, which may be adjusted to change the amount of heat produced in the material being treated. Such control provides the operator with complete and instantaneous adjustments of the heating without time lag, which is not possible with other prior methods of heating.

One advantage of the apparatus illustrated resides in the fact that, within limits, variations in the amount of water, solvent, or other liquid in the cord are automatically compensated for to produce a cord that can be treated more nearly uniformly than it could be by other prior methods or devices. It is well known that a material of higher electrical power loss absorbs more electrical energy, and hence generates more heat within itself than a material of lower power loss. Since the power loss of water is higher than

cotton fibers, the heat generated in the cord will vary directly with the moisture content thereof. Changes in the moisture content of the cord as it moves through the apparatus utilize the electrical energy of a correspondingly varying number of plates. In the manner in which the electrodes are designed, the overall impedance of the load circuit, which includes both the electrode and the material being treated, remains substantially constant although the moisture content of the material may vary considerably from the average. As will be apparent from the above description, the electrodes essentially comprise a plurality of condensers connected in parallel with each other, in view of which a relatively high impedance is provided which is affected more by the total fixed reactance than by the series resistance of the load. The formula for impedance Z of a condenser having a reactance X and a dielectric, the power loss through which is R , as an equivalent series resistance, is

$$Z = \sqrt{X^2 + R^2}$$

Since X is a constant composed of the total reactances of all the condensers which comprise the electrode, it is very large in comparison with the changes in resistance R due to the changes in the power loss of the dielectric as the cord dries. The overall impedance of the circuit, therefore, varies little with relatively large changes of moisture, and the generator may operate with constant output and maximum efficiency without requiring continuing adjustments to correspond to a change of impedance due to moisture variation in the cord.

I have found that with a generator having an energy output of 1 kw., 35 percent moisture in 17/4/3 cotton cord can be reduced to a minimum of 6 percent by approximately 5 seconds exposure to the electrostatic field, the cord being moved through the electrodes at a rate of about 144 yards per minute.

In Figures 1, 2, and 3, the plates 18 are illustrated as being equidistantly spaced. However, in some instances, it is advantageous to use differential spacing. For example, by spacing the first plates farther apart from each other than the last plates of the series, the cord moving through the electrostatic field is subjected to gradual increasing intensities of energy. If it is desired to subject the cord to decreasing intensities of energy, the spacing may be reversed. Also, any intermediate effects of increasing and decreasing of energy may be provided.

A plurality of the units may be electrically connected together in any of the well-known types of electrical circuits, such as in series, parallel or series-parallel to provide a flexible method of obtaining desired heating effects and to permit the control of the number of plates which a single generator may resonate. In any of the circuit arrangements, any electrode, or any plurality of electrodes of the same instantaneous polarity, may be grounded without significantly affecting the operation of the apparatus. The size and shape of the individual plates of the electrodes may be modified to adapt them to the material to be treated.

Where it is desired to treat a number of cords simultaneously, the embodiment illustrated in Figure 4 may be used where the plate 27 is elongated and the aperture 28 therethrough is similarly elongated. Although it is not indispensable, it is preferred that the width of the aperture 28 be substantially one-third the width

of the plate. A certain amount of electrostatic field concentrates at the points 29, 29 of the plates. It is, therefore, important that the aperture 28 be sufficiently long so that the outermost cords 30, 30 are not too close to these points of concentration. To facilitate placing the cords through the plates, each plate is provided with a slot 31, which passes from the aperture 28 to the exterior. However, this feature is not indispensable and may be eliminated, if desired. Although the slot may be disposed at any point on the plate, it has been found that its location at the end of the major axis of the orifice is most satisfactory.

In Figure 5, there is illustrated an embodiment wherein the entire end of each plate 32 is open, and the plate is mounted with the major axis in a vertical position. This may be referred to as a horseshoe or U-type, and it has the advantage that when material is being treated which emits vapors, the tendency to flashover is reduced due to the fact that the vapor is provided with an unrestricted path to the atmosphere above the plates.

The embodiment illustrated in Figure 6 is preferred for the heating of sheeting or fabric in wide widths. This embodiment is similar to the one illustrated in Figure 4, except that instead of providing a slot for the introduction of the material, the plate is fabricated into two parts 33 and 34, which are hinged together substantially as shown. The lower half is secured to the bracket 35 and may be considered the stationary half, while the upper half may be moved to an open position for the purpose of admitting the material to be treated and then pushed down again into closed position. In order to insure a satisfactory electrical connection between the two halves of the plate and to obviate any power loss or sparking which may occur at the hinge point, a flexible metallic strip 36 may be provided to connect the two halves of the plate electrically and insure a satisfactory electrical connection.

In operating any of the embodiments illustrated above, it is not necessary to maintain them in any particular position relative to the horizontal or vertical. To suit the convenience of any particular operation, the plates may be disposed in any special position desired so long as the same axial relationship exists among the plates.

Having thus described my invention, I claim:

5 A heating device for continuous heating of sheets and filaments, comprising a row of at least four relatively thin flat electrode plates, said electrode plates being disposed in spaced, parallel relation facing each other and having aligned openings through which a material to be heated may be made to pass from one electrode to the other, the distance between consecutive electrodes being substantially greater than the thickness of the electrodes and in an amount sufficient to prevent electrical flashover under the influence of vapor rising from the material, the flat faces of the plates having no lateral projections, means for supporting said electrodes and 10 for securing them in position, and means for establishing a high frequency electrostatic field across each consecutive pair of electrodes, whereby a series of contiguous electrostatic fields may be established in a path surrounding the longitudinal axis of the aligned openings, said electrodes being fabricated of two half sections hinged together at one side, one section being secured in position, the other section being movable about the hinge to open the electrode and 15 facilitate threading through of the sheet or filament, and guide rolls for continuously feeding and removing the sheet or filament.
